D-530

No. 530. —

#1 Sath' Chapin's Design for Stat. Blind
Patented Nov. 30, 1852. —

Rec. 530

Nathan Chapin of New York N.Y.

Assignee to

Nathan Chapin and John F. Briggs of New York (affore aid)

Letter Patent No 530 Dated Nov 30 1852.

mmmm

The schedule referred to in these Lettered Patent and making part of the same

mmmm

To all whom it may concern.

Be it known that I Nathan Chapin of the City, County and State of New York, have invented or produced a new and original design for Slat Blinds for windows, which I denominate the Ware line Venetian slat and I do hereby declare that the said design is substantially described by the drawings annexed and forming part of this speci

2

Ales. 539

ation of which c.c. represents the configuration of the edges of each slat comprising the Blind: being two waved lines drawn parallel to each other on a flat surface.

I wish to patent the design, irrespective of the size or manner of hanging the slats of the blind and limit my claim to the wave line, given the edges on the front and back edge of each slat: thus making an ornamental blind producing an agreeable wave line of light between the slats.

What I claim and desire to secure by letter patent is the Design or configuration given the slats of Window-blinds as above described and set forth in the annexed drawings

In testimony whereof I have hereunto signed my name before two subscribing witnesses
